UNITED STATES PATENT OFFICE.

EDWARD C. DUER, OF VENICE, CALIFORNIA.

PUMPING APPARATUS.

Application filed October 10, 1921. Serial No. 506,865.

To all whom it may concern:

Be it known that I, EDWARD C. DUER, a citizen of the United States, residing in Venice, in the county of Los Angeles and 5 State of California, have invented certain new and useful Improvements in Pumping Apparatus, of which the following is a specification.

This invention relates to pumping apparatus of the kind in which the flow of water, oil or other liquid is maintained without the aid of vacuum or air pressure by valved pistons operating in pipes at different speeds and in which the liquid is lifted by the pistons by successive impulses. The object of 10 the invention is to provide novel means for admitting the liquid to the pipes and for raising it to the point of delivery and a further object of the invention is to provide 15 novel and improved means whereby two or more pumps may be simultaneously operated in such manner as to provide a counterbalancing of the liquid and the weight of the pumps, the pumps being operated 20 in such manner that a minimum amount of power is required. The construction of the apparatus is such as to operate to lift the liquid from any desired depth without the aid of air pressure or vacuum 25 and the flow of liquid is made continuous. The apparatus differs from force pumps in which a rapid or forceful flow of the liquid is desired and it is especially intended for raising water from wells, pits and other 30 places on farm lands and oil fields for irrigating purposes, but the apparatus may be used for raising liquids of various kinds 35 in various places.

In carrying out my invention in the preferred way, I employ duplicate pumping apparatus consisting of two pipes or casings arranged side by side and in each of these pipes or casings I arrange two pistons having piston rods extending up through the 40 casing to mechanism which operates the pistons at different speeds and to different extents. Each piston is provided with valves opening upwardly and the arrangement is such that on the down stroke of the pistons the lower one moves faster and 45 further than the upper one and the liquid passes through the lower piston and enters in the casing between the upper and lower pistons. At this time the water in the casing 50 above the pistons rests on the upper piston. On the upstroke of the two pistons the

lower piston moves faster than the upper one and further. At this time the valves in the lower piston are closed. The valves in the upper piston remain open until the 60 lower piston arrives close to the upper one, and the liquid is lifted by the lower piston and discharged through the upper piston and through a suitable discharge opening. In this way liquid is raised from any desired 65 depth, the apparatus being entirely practicable for raising water three hundred feet or more and for raising oil three thousand feet or more. As before stated, in order to counterbalance the weight of the 70 water and the operating mechanism, I employ two sets of pumping apparatus which are connected to be operated simultaneously by the same power and in such manner that the weight of one counterbalances that of 75 the other. The apparatus is so organized that when one set of pistons in one casing is being moved downward the other set is being moved upward. The mechanism for operating the pistons comprises a walking beam mounted in a suitable frame and on suitable standards to turn about a horizontal axis. The walking beam at one end is link-connected with the piston rod of the lower piston and is connected by a slot and 80 pin connection with the piston rod of the upper piston. The piston rods of the other pump are similarly connected to the opposite end of the walking beam, which latter is provided with an arm to which power 85 is applied to oscillate the walking beam and operate the pistons.

My improvements are illustrated in the accompanying drawings, in which

Figure 1 is a view, partly in front elevation, and partly in section of the apparatus;

Figure 2 is a side elevation of the same;

Figure 3 is a view similar to Fig. 1, but showing the operating mechanism in a different position or one in which the pistons in the two casings are at the same level;

Figure 4 is a detail view in section and on an enlarged scale showing more clearly the construction of the pistons and their valves; and

Figure 5 shows a transverse section on the line 5—5 of Fig. 4.

It will be understood that the apparatus is intended to raise water, oil or other liquids from a considerable depth and the pumping apparatus is suitably mounted on the

ground level, the piston casings passing through the ground to the required depth and the operating mechanism being located above ground.

- 5 A suitable platform A may be employed on the ground and pipes or casings B are sunk the required distance to the water, oil or liquid to be raised. These pipes or casings B may be connected with the platform 10 at b in any suitable way and these pipes or casings may be connected by branches to a delivery pipe C in the manner shown in Fig. 1, at B' or the casing B on one side of the apparatus may be connected with the 15 casing B on the other side of the apparatus by a cross connection B' and the liquid from both casings may be discharged through a delivery pipe D. There are two pistons E, F, in each casing B and these pistons are 20 connected with the piston-operating mechanism above the ground level. This mechanism comprises a walking beam G, which is pivotally mounted at g on standards H. The walking beam has a downwardly ex- 25 tending arm J, which is connected to a rod K. This rod may be operated by any suitable engine to oscillate the walking beam about its horizontal axis. The piston E is connected by a rod L to a shoe M, which is 30 adapted to move vertically in the frame N. This shoe is connected by the link O with the outer portion of one end of the walking beam. The piston F is connected by a piston rod P with the walking beam between its middle portion and its outer end by a slot and 35 pin connection indicated at x. As the walking beam is operated the pistons E and F are reciprocated vertically, but by reason of the connections shown the piston E is moved 40 faster and to a greater extent than the piston F. They, however, move downwards at the same time and upwards at the same time. The pistons E and F in the two pumps are constructed and operated in the same way. 45 As indicated in Fig. 4 the piston E comprises a casing e, which has openings e' in it and there is a partition e'', which has openings through it and above the partition there are ball valves e⁴. Above the ball valves 50 there are stops e² in the piston which limit the upward movement of the balls. The rod L extends through a central sleeve of the piston E and is secured firmly thereto. The piston F is of the same general construction as the piston E, having openings f' through it and a partition f'', and this piston is equipped with ball valves f⁴ and stops f². The piston F, however, has a central sleeve f⁵, which is not secured to the 55 rod L, but the rod L passes freely through it. The piston F is firmly attached to a part P' of the piston rod P which, as shown in Fig. 4, is tubular, permitting the piston rod L to move freely in it. The two rods are so 60 formed that they may operate simultane- 65

ously, but independently of each other. The rods pass through a closure m, which prevents the liquid from rising above the cross connection B' of the pipes. The rods pass through frames Q, which serve to guide the 70 rods and these frames may be connected with the standards H by brackets q. It will be observed that each side of the frame N comprises two beams or rods and the shoe M operates between them. The upper end of 75 the rod P has a loop formed as indicated in Fig. 2 to straddle the walking beam. The slot and pin connection is shown in Fig. 2 at x. The rod P is attached to the tube P', to which the piston F is secured by straps or 80 other suitable devices p, as indicated in Fig. 1. The tube P' may be of any suitable length. In this way it will be observed that the rods P and L may be arranged side by side, the rod L passing through the tube P', 85 while the rod P is set to one side of the rod L. In this way the two rods may operate without interference.

In Fig. 1 the pistons of the right-hand side of the apparatus are shown in their 90 uppermost position and the pistons on the left-hand side in their lowermost position. The walking beam on the right-hand side of the apparatus is raised to its full extent and is ready to commence a down stroke. 95 On the down stroke of this end of the walking beam the pistons E and F are forced downwards. The piston E travels faster than the piston F and moves further. As the piston E descends, the valves e⁴ open, 100 water is admitted through the casing B and passes through the piston into the space between the two pistons E and F. The valves f⁴ in the piston F remain closed. When the pistons reach the position shown 105 at the left-hand side of the apparatus in Fig. 1, water is contained between the two pistons and on the up stroke the valves e⁴ of the piston E close and liquid is lifted and is forced through the piston F into the casing 110 above said piston F. When the two pistons have reached the position shown at the right-hand side of Fig. 1, the liquid is held in the casing B above the pistons. By the repeated operation of the pistons water 115 is thus lifted and forced out through the discharge pipe C or D. It will be observed that the construction of the apparatus is such that a continuous flow of liquid may be maintained. As one set of pistons is descending the 120 other set is rising and by rapid operation of the mechanism a continuous flow is produced. It will be understood that this flow is not with any great force and the liquid is not discharged at a distance, but the apparatus is 125 very useful for use in oil fields and farm lands, where liquid may be drawn from various depths and delivered on the land, or to suitable receptacles. The water level in Figs. 1 and 3 is indicated at W by the dotted 130

lines. It will be understood that the casings descend into the water wherever it be located. Any back flow following the downward movement of the pistons does not interfere with their operation because when the pistons descend the valves β^4 in the piston F are closed and the liquid does not pass by this piston. When the pistons commence to rise the liquid is forced through

10 the piston F and causes the back flow liquid to be expelled and an additional supply of liquid to enter the casing above the upper piston. No liquid ever passes downwards past the valve F.

15 By constructing the apparatus in the manner shown and above described, and operating it in the way indicated, the weight of the pistons and their actuating apparatus and the weight of the water is counterbalanced so that comparatively small power is required to operate the pumps. A single pump may be used in some cases where power is abundant or is not a consideration, but I prefer to employ duplicate pumps, 20 as illustrated. It will also be understood that the number of pumps may be multiplied, if desired, and all operated by the same power, the pumps being arranged in pairs or in an equivalent way to provide the 25 counterbalancing effect hereinbefore explained. When using one pump a counterbalancing weight may be employed on one side of the walking beam.

I claim as my invention:

30 1. Pumping apparatus, comprising a tubular casing, upper and lower pistons pro-

vided with valves and mounted to reciprocate therein, a walking beam, a piston rod extending from the lower piston in the casing, a link connection between the upper 40 end of this piston rod and the outer end of the walking beam, a piston rod connected with the upper piston, and a slot and pin connection between this piston rod and the walking beam.

45 2. Pumping apparatus comprising a plurality of tubular casings, upper and lower valved pistons in each casing, a walking beam, a piston rod extending from each lower piston, means for connecting these piston rods with the ends of the walking beam, a piston rod extending from each upper piston, and means connecting these piston rods with the walking beam at points nearer its center, whereby the pistons in one casing 50 are raised as the others are lowered, and whereby the upper pistons reciprocate more slowly than the lower.

3. Pumping apparatus comprising a plurality of tubular casings, upper and lower 55 pistons having valves and mounted to reciprocate in each casing, a walking beam, piston rods extending from the lower pistons, link connections between these piston rods and the ends of the walking beam, piston rods connected with the upper pistons, and slot and pin connections between these piston rods and the walking beam.

In testimony whereof, I have hereunto subscribed my name.

EDWARD C. DUER.
